PANTY GIRDLE

Harry Steiner, Belle Harbor, N.Y., assignor to Kops Bros. Inc., New York, N.Y., a corporation of New York

Filed May 19, 1969, Ser. No. 17,217

Term of patent 14 years

Int. Cl. D2—02

U.S. Cl. D2—4

FIG. 1.

FIG. 2.

FIG. 3.

FIG. 4.

FIG. 6.

FIG. 1 is a front perspective view of a panty girdle, showing my new design with one leg portion raised;

FIG. 2 is a front elevational view of the panty girdle;

FIG. 3 is a side elevation view thereof;

FIG. 4 is a side elevational view of the side opposite that shown in FIG. 3;

FIG. 5 is a rear elevation view; and

FIG. 6 is an enlarged fragmentary view of the outside leg portion of the panty girdle.

I claim:

The ornamental design for a panty girdle, substantially as shown.
